TAMPER AND LIKE IMPACT TOOL

Corwill Jackson, Chicago, Ill.

Application August 20, 1930, Serial No. 476,606

5 Claims. (Cl. 125—33)

I have illustrated my improvements in the accompanying drawing as adapted by me for tie tampers, although the structure illustrated, with proper modification in the tool, is adapted for use 5 in other relations.

The main objects of this invention are:

First, to provide an improved impact tool of 10 the class described which is highly efficient and convenient to use with little effort on the part 10 of the operator.

Second, to provide an impact tool which enables 15 the performance of a very large amount of work by an operator.

Objects relating to details and economies of my 15 invention will appear from the description to follow. The invention is defined and pointed out in the claims.

A structure which is a preferred embodiment 20 of my invention is illustrated in the accompanying drawing, in which:

Fig. 1 is a side elevation of my improved tool 25 partially broken away and partially in vertical central section.

Fig. 2 is an enlarged fragmentary view partially 25 in section on line 2—2 of Fig. 1.

Referring to the drawing, I provide a casing-like body 1 having an electric motor housed therein, the rotor 2 of the motor being provided with a shaft 3 supported by bearings 4 and 5. On this 30 shaft and between the bearings I mount an oval cam 6.

The cylindrical tool holder socket 7 is preferably formed integrally with a part of the casing and is shouldered at 8. At its outer end this 35 socket is provided with laterally projecting ears 9.

Within the socket I arrange a bushing 10 for the tappet 11. This tappet is provided with a shoulder 12 coaxing with the outer end of the bushing thereby limiting the inward movement of 40 the tappet. The tappet is supported in the bushing both for reciprocating and rotative movement.

Shims 13 are arranged between the shoulder 45 8 and the flange on the bushing so that the position of the tappet relative to the cam is controlled by the number of these shims; that is, by inserting or removing shims, the inner position of the inner end of the tappet is controlled. The right 50 face at the inner end of the tappet is preferably flat so that its rotation does not affect its relation to the cam but it may rotate to distribute the wear thereon and it is found in practice that it does rotate so that the wear on the tappet is slight and is very uniformly distributed.

55 The tool 14 is supported in operative relation to

the tappet by means of the holder 15, the inner end of which is engaged in the tool holder socket thereby holding the same in proper alignment. The tool and tool holder have non-circular portions which prevent rotative movement of the tool in the holder.

The tool is provided with a collar-like enlargement 16 coaxing with the ends of the enlargement 17 in the tool holder to limit the stroke of the tool relative to the holder, the shoulder 18 10 at the outer end of the enlargement 17 particularly serving as a stop.

In operation, the tool is brought into coaxing relation with the tappet by an upward thrust on the tool; that is, when the tool is allowed to rest 15 on ballast for instance, it is forced upward into engagement with the tappet as shown in Fig. 2.

To relieve shock when operated on very light or yielding material the tool holder is yieldingly mounted, it being provided with ears 19 disposed oppositely of the ears 9 on the tool holder socket. Bolts 20 arranged through these ears carry the springs 21 arranged between the ears 9 and the nuts 22 on the upper ends of the bolts which 25 constitute thrust members. Buffers 23 are arranged between the ears.

The casing-like body is provided with a handle 24.

I preferably provide means for automatically lubricating the impact wheel and tappet, this means consisting of a lubricant reservoir 25 and the wick 26 which is folded upon itself to depend from the central holder 27 into the path of the cam so that, as the cam rotates, its nose comes into contact with the wick and lubricant is applied to the cam and carried thereby to the face of the tappet. The result is that these parts are 30 efficiently lubricated without excessive use of lubricant and without the necessity of providing tight joints such as would be required if the cam 35 rotated in a lubricant holding chamber.

My improved tool is highly efficient when employed as a tie tamper, and enables the performance of a large amount of work with a comparatively small amount of effort on the part of the 40 operator.

When the tool is in engagement with the work, the oval cam 6 acts to produce a rapid series of pressure impulses.

In use, the tool rests upon the work or material 50 to be tamped and supports the weight of the casing-like body and the parts carried thereby, the handle being provided for manipulating the tool from place to place upon the work and holding the machine in upright position.

In the commercial structure, the casing weighs approximately 70 pounds so that operation of the machine does not give a series of hammer-like blows but a rapid series of impulses backed by this weight, the force of the impulses being equal to the weight of the casing so that there is, in effect, a series of heavy pushes as distinguished from hammer-like blows.

This not only results in effective packing of the material but accomplishes this result without crushing the ballast as occurs with pneumatic tools and the like where the hammer-like blow is present.

I have illustrated and described my improvements in an embodiment which I have found highly satisfactory. I have not attempted to illustrate or describe certain other embodiments and adaptations as it is believed that this disclosure will enable those skilled in the art to embody or adapt the same as may be desired.

Having thus described my invention, what I claim as new and desire to secure by Letters Patent, is:

1. In a structure of the class described, the combination of a casing-like body having a shouldered tool socket with laterally projecting ears at its outer end, a motor mounted within said casing and provided with a shaft disposed transversely of said socket, an oval cam on said shaft, said shaft being provided with supporting bearings at each side of said cam, a bushing for said socket having an out-turned flange at its lower end disposed in opposed relation to said shoulder of said socket, there being a plurality of adjusting shims disposed between said shoulder and flange, a shouldered tappet rotatively and reciprocatingly mounted in said bushing in coacting relation to said cam with its shoulder coacting with the end of the bushing to limit the inward movement of the tappet, said tappet having a substantially flat right face at its inner end coacting with said cam, a tool holder engaged in said tool holder socket and provided with laterally projecting ears disposed oppositely to said ears on said tool holder socket, bolts arranged through said ears on said tool holder and tool holder socket, springs on said bolts whereby said tool holder is yieldingly supported, and a tool reciprocatingly mounted in said tool holder in coacting relation to said tappet and adapted when applied to the work to constitute a support for the body and parts carried thereby, said tool and tool holder having coacting stops limiting the outward movement of the tool.

2. In a structure of the class described, the combination of a casing-like body having a shouldered tool socket, a motor mounted within said casing and provided with a shaft disposed transversely of said socket, an oval cam on said shaft, said shaft being provided with supporting bearings at each side of said cam, a bushing for said socket having an out-turned flange at its lower end disposed in opposed relation to said shoulder of said socket, there being a plurality of adjusting shims disposed between said shoulder and flange, a shouldered tappet rotatively and reciprocatingly mounted in said bushing in coacting relation to said cam with its shoulder coacting with the end of the bushing to limit the inward movement of the tappet, said tappet having a face at its inner end coacting with said cam, a tool holder engaged in said tool holder socket, and a tool reciprocatingly mounted in said tool holder in coacting relation to said tappet.

of the bushing to limit the inward movement of the tappet, said tappet having a substantially flat right face at its inner end coacting with said cam, a tool holder engaged in said tool holder socket, and a tool reciprocatingly mounted in said tool holder in coacting relation to said tappet and adapted when applied to the work to constitute a support for the body and parts carried thereby, said tool and tool holder having coacting stops limiting the outward movement of the tool.

3. In a structure of the class described, the combination of a casing-like body having a shouldered tool socket, a motor mounted within said casing and provided with a shaft disposed transversely of said socket, a cam on said shaft, said shaft being provided with supporting bearings at each side of said cam, a bushing for said socket having an out-turned flange at its lower end disposed in opposed relation to said shoulder of said socket, there being a plurality of adjusting shims disposed between said shoulder and flange, a shouldered tappet rotatively and reciprocatingly mounted in said bushing in coacting relation to said cam with its shoulder coacting with the end of the bushing to limit the inward movement of the tappet, said tappet having a face at its inner end coacting with said cam, a tool holder engaged in said tool holder socket, and a tool reciprocatingly mounted in said tool holder in coacting relation to said tappet.

4. In a structure of the class described, the combination of a casing-like body having a shouldered tool socket, a motor mounted within said casing and provided with a shaft disposed transversely of said socket, a cam on said shaft, a bushing for said socket having an out-turned flange at its lower end disposed in opposed relation to said shoulder of said socket, adjusting means disposed between said shoulder and flange, a shouldered tappet rotatively and reciprocatingly mounted in said bushing in coacting relation to said cam with its shoulder coacting with the end of the bushing to limit the inward movement of the tappet, said tappet having a face at its inner end coacting with said cam, a tool holder engaged in said tool holder socket, and a tool reciprocatingly mounted in said tool holder in coacting relation to said tappet.

5. In a structure of the class described, the combination of a casing having an elongated bore provided with an enlarged end portion forming a shoulder, an elongated bushing fitting said bore and having an end flange fitting said enlarged end portion thereof, shims disposed between said shoulder and flange, a tool holder mounted on said casing and having an internally shouldered socket telescoped within said enlarged end portion of the bore and engaging said end flange of the bushing, and a tappet disposed through said bushing and having a flange in said socket coacting with the shoulder thereof and the end flange of said bushing to limit the travel of the tappet, the position of the latter relative to the casing being changed by varying the number of said shims.

CORWILL JACKSON.
